GAME BOARD

Louis Tartack, 2427 S. Hutchinson St., Philadelphia,
Pa. 19148, and Raymond Jannetti, 805 Rocklynn
Road, Springfield, Pa. 19064

Filed Oct. 30, 1967, Ser. No. 9,210

Term of patent 14 years

Int. Cl. D21—01

U.S. Cl. D34—5

FIG. 1 is a top plan view of a game board showing our new design.

FIG. 2 is a side elevational view thereof.

The dominant features of our design reside in the full line portions shown.

We claim:

The ornamental design for a game board, as shown and described.
